KITCHEN CABINET

Filed April 30, 1924

UNITED STATES PATENT OFFICE.

MARIE P. LEEDS, OF NEW YORK, N. Y.

KITCHEN CABINET.

Application filed April 30, 1924. Serial No. 710,060.

My invention relates to kitchen cabinets and more particularly to a cabinet which is so constructed that it will conveniently contain a kitchen range or stove, and also cooking appliances, serving plates and dishes.

One object of this invention is to provide a cabinet which when placed in position around a kitchen range or stove, will serve to conceal the stove when it is not being used. When it is desired to use the stove for any purpose, the doors of the cabinet are opened, and the stove is thus made available for service.

Another object of this invention is to provide a cabinet whereby meats, vegetable plates and other dishes may be kept hot while the meals are cooking and at no extra expense of fuel.

Another object of this invention is to provide a cabinet for the above described purposes of a knock-down type so as to make the shipping and installation of the cabinet simple and inexpensive.

My invention consists in the parts, improvements and combinations more fully pointed out hereinafter.

Referring to the drawings:

Figure 1 is a front view of a cabinet embodying my invention with one door removed and the other door detached.

Figure 2 is a plan view of the cabinet with the top removed.

Figure 3 is a side view with one side removed.

Figure 4 is a detail view of one of the lining plates.

Figure 5 is a detail view showing the assembly of the lining plate, the side and one of the connecting-supporting rods.

Figure 6 is a detail view illustrating means for securing a side to a back plate.

As illustrated, the cabinet is a knock-down cabinet but it may, of course, remain permanently in place. It may be composed of two sides, a back plate, two doors, or one as desired, hung in front, a top, a plurality of shelves, lining plates and cross rods.

The sides 1 fit into or engage with the grooves 2^a in the top 2 and the doors in front are fastened thereto, preferably with hinges 3. Lining plates 4 are provided made of metal or of any suitable material which will serve to protect against heat. These are hung one on each side and arranged so that there shall be an air space between the sides of the cabinet and the insulating plates.

Metal connecting-supporting rods 5 are provided for the support of the shelves 6 made of heat resisting material.

The connecting-supporting rods 5 which support the shelves 6, extend thru holes 7 cut in the lining plates 4 and are hooked into eye-screws 8 or any other convenient fastening means fastened to the inside of the sides 1 of the cabinet (see Figures 2 and 5), so that the shelves may be readily detached from the rods. The rods may be removed when raised.

The back 100 may be removably secured to the sides by clamps 101 and screws 102.

With a range or stove, in this example, a gas range, there may be a floor 9 to the cabinet, but generally the floor on which the stove is set is convenient as a floor, and in such cases the cabinet can be installed around the stove without a cabinet floor or bottom.

In erecting the cabinet, the sides 1 are first set up and the top 2 placed thereon, care being taken to have the grooves 2^a fit down over the sides. The metal lining plates 4 are then placed near the inside of the sides 1 and the sides connected by means of the connecting-supporting rods 5, by inserting the ends of the rods 5 thru the holes 7 and then by inserting the hooked ends in the screw eyes 8.

The metal shelves 6 are then laid on the connecting-supporting rods 5 and serve a double purpose, that is shelves for holding various utensils used in the kitchen, and being made to the proper length, when properly assembled the metal lining plates 4 are kept vertical and are forced out flush against the two side ends of the metal shelves 6 leaving an insulating air space between the inside of the sides and the metal lining plates 4.

The width of the insulating air space to be provided is regulated by the length of the connecting-supporting rods 5. The holes 7 in the lining plates 4 and the screw eyes 8 are arranged so that proper adjustment of the various shelves may be made. Three strips 50 of wood or other material can be fastened to the inside of each of the two sides 1, at the top, center and bottom, running from front to back, to serve as an additional means of keeping true the heat insulating spaces between the sides 1 and the plates 4.

Then the doors 9 are fastened by means of hinges 3 or otherwise to the front of the two sides or the cabinet may be made with one door, hung at either side, as may be most

convenient to fit the space the cabinet is to occupy in use.

When the cabinet is installed it contains and surrounds the kitchen range so that the latter is entirely concealed when the cabinet doors are closed, and only what appears to be an ordinary cabinet is seen, but, when the cabinet door or doors are opened, the range may be used for cooking purposes as if there were no cabinet, but more conveniently and economically for the inside of the doors may be provided with baskets 25 to hold knives, forks, spoons or other small articles, and hooks 26 for hanging utensils and with the shelving 6 provided, plates and food can be kept hot during the process of cooking, and extra gas need not be used for this purpose.

Gas is connected thru a pipe passing thru the cut-out 27 to be placed at the point most convenient to the meter.

When shipping or moving the cabinet, it can be easily taken apart or knocked down.

The cabinet has a number of advantages. In using it one can cook in a room which may be a living room and by simply closing the doors of the cabinet the cook stove is concealed from view. It keeps the food and plates hot. By keeping the doors closed while cooking time is saved in the operation by reason of the confined heat.

Having thus described the invention its construction will be clear, and it will be understood changes may be made without departing from the principle of the invention.

What I claim and desire to secure by Letters Patent is:

1. A cabinet for stoves comprising two sides, a metal lining for each side, spaced therefrom and provided with holes, a top connecting-supporting rods connecting the sides and extending between the sides and thru the holes in said linings, shelves re-

movably supported on said rods and doors carried by the sides. 45

2. A cabinet comprising two sides, and a top, fastening means carried by the sides, connecting rods engaging the fastening means, metal linings being spaced from the sides and carried by the rods, said linings 50 provided with holes thru which the rods pass.

3. A knock-down cabinet comprising two sides, a top provided with recesses at both edges into which the sides will fit, laterally extending supporting means for the sides extending from one side to the other, metal linings for said sides spaced from the sides and supported by the said laterally extending supporting means and shelves fitting 60 between the said metal linings. 55

4. A knock-down cabinet comprising sides, top, back and doors for the front, each part made a separate unit detachable at will, shelves and connecting and supporting cross rods for the said sides in detachable engagement with the latter, metal linings which are supported on the said cross rods, and shelves placed, upon the latter and abutting said metal linings. 65 70

5. A knock-down cabinet comprising sides, made of suitable material, a top made with recesses at each edge of the top for the insertion of the sides, fastening means carried by the sides, lateral rods engaging the fastening means, the rods extending from one side to the other across the interior of the cabinet, metal linings supported by said rods and provided with holes to receive the rods, shelves on the rods abutting said metal linings, a metal back and a door hung from the front of a side. 75 80

In testimony whereof, I have signed this specification.

MARIE P. LEEDS.
